MEMO HOLDER

Norbert Leopoldi, 4180 Marine Drive,
Chicago, Ill. 60613

Filed June 19, 1972, Ser. No. 263,957

Term of patent 14 years

Int. Cl. D19—02

U.S. Cl. D74—2 B

FIG. 1 is a front elevational view of a memo holder showing my new design;

FIG. 2 is an enlarged scale rear perspective view;

FIG. 3 is a right side elevational view partly in vertical section taken substantially on the line 3—3 of FIG. 1, an intermediate portion of the vertical member being broken away for ease of illustration; and

FIG. 4 is an enlarged scale horizontal sectional view taken on line 4—4 of FIG. 3.

I claim:

The ornamental design for a memo holder; substantially as shown and described.
